UNITED STATES PATENT OFFICE.

ROBERT C. WERKHEISER, OF WILKES-BARRE, PENNSYLVANIA.

TOE-CAP FOR BOOTS AND SHOES.

1,115,045.

Specification of Letters Patent.

Patented Oct. 27, 1914.

Application filed August 29, 1912. Serial No. 717,782.

To all whom it may concern:

Be it known that I, ROBERT C. WERKHEISER, a citizen of the United States, residing at Wilkes-Barre, in the county of 5 Luzerne and State of Pennsylvania, have invented certain new and useful Improvements in Toe-Caps for Boots and Shoes; and I do hereby declare the following to be a full, clear, and exact description of the invention, 10 such as will enable others skilled in the art to which it appertains to make and use the same.

My invention relates to new and useful improvements in protecting caps for the 15 toes of boots and shoes and the object of my invention is to provide a protecting cap for the toes of boots and shoes which will effectually protect said toes from wear and injury due to striking against objects.

20 With this object in view, the invention consists of the improved construction, arrangement and combination of the parts of a device of the character described, and afterward specifically claimed.

25 In the accompanying drawings I have shown the preferred forms which my invention may take.

In said drawings, Figure 1 is a perspective view of a boot showing an approved form 30 of my invention secured over the toe thereof. Fig. 2 is a detail sectional view through the toe of the boot and the form of cap shown in Fig. 1. Fig. 3 is a perspective view of a portion of a toe of a boot or shoe 35 having modified means for securing the cap to the sole. Fig. 4 is a detail sectional view therethrough, and, Fig. 5 is a perspective view of a portion of a toe of a boot or shoe having still further modified means for se- 40 curing the cap to the sole.

Referring to the drawings by numerals of reference, the same numeral designating corresponding parts throughout the several figures, 5 indicates a protecting cap adapted 45 to be secured upon the toe of a boot or shoe and formed with a concave portion 6 to fit over the upper of the toe, said portion 6 being provided at its lower edge with a channel rim 7 adapted to closely fit the forward 50 edge of the sole of the shoe or boot. The lower portion of the rim 7 is countersunk in the sole so as to be flush with the lower surface thereof. The cap is adapted to be secured in position by a rivet 8 extending 55 therethrough and through the upper of the toe of the shoe, and in this instance, by a

screw 9 extending through the rim 7 and into the sole of the shoe, as clearly shown in Fig. 2. The form of cap just described will closely fit the contour of the boot or 60 shoe and will effectually protect the forward end of the sole and the toe of the shoe or boot from injury.

In Figs. 3 and 4 I have shown modified means for securing the cap to the sole in 65 which the protecting cap 10 is formed so as to extend from the forward edge of the sole and over the end of the toe. The outer surface of the protecting cap 10 is smooth, 70 as clearly shown, and it is provided with the rivet 8 and at either side with tongues 11, which serve the double purpose of bracing and keeping rigid the shield and keeping out dirt and mud, and which are pointed and formed with upper curved edges and 75 lower straight edges so that when bent inwardly they will be flush with the curved lower portion of the cap and with the straight upper edge of the sole, as clearly shown in Fig. 3. This form of cap is adapt- 80 ed to be secured to the sole in any desired manner, but preferably by means of a screw 12, which extends through said cap and into the shoe between the upper and the sole thereof, the threads of the screw 10 engag- 85 ing in the leather thereof, said screw being unsupported by said shield. The securing screws 9 and 12 are countersunk in the rim 7 and cap 10 so as not to project beyond the surface and form points upon which objects 90 might catch.

In Fig. 5, I have shown a still further modified means for securing the cap to the sole in which the cap 13 is formed to closely fit the toe of a shoe or boot, as in Fig. 4, and 95 is provided with a centrally disposed projecting tongue 14 arranged to extend downwardly to the lower edge of the front of the sole of the shoe and with a tongue 15 at either side adapted to be bent inwardly between the sole and upper. This means for securing the cap to the sole is particularly adapted to be used in connection with a shoe or boot which has been subjected to considerable wear, as the parts of the cap may be 100 easily bent into the desired shape.

While I have shown the preferred forms of my invention, I desire it to be understood that other modifications in the manner of securing the cap to the sole may be made 110 without departing from the spirit and scope of the invention.

What I claim as new and desire to secure by Letters-Patent of the United States is:

A tip shield for the toes of boots or shoes comprising a sheet metal cap arranged to fit the toe of a shoe, the lower edge of said cap being arranged flush with the sole of the boot or shoe and the body of said cap being arranged to extend upwardly and cover the toe of the upper, and pointed tongues at the opposite side edges of the body, said tongues having upper curved edges and

lower straight edges arranged to be snugly fitted between said sole and said upper, said cap being arranged to be fastened to said upper.

In testimony whereof I have signed my name to this specification in the presence of two subscribing witnesses.

ROBERT C. WERKHEISER.
